TOOL FOR USE ON PLASTER OR
THE LIKE

Leslie J. Eiden, Los Angeles, and Clifford R. Magers, Tarzana, Calif.; said Eiden assignor to Robert L. Hoffmann, San Jose, Calif.

Application June 20, 1949, Serial No. 100,172

6 Claims. (Cl. 72—136)

1

This invention has to do with a tool for use on plaster or the like, it being a general object of the invention to provide a practical, improved tool of the general type commonly referred to as a float.

In the working or application of plaster and like materials there are operations which require tools known as floats and it is through the use of such tools that various conditions are brought about or surfaces are developed or established. For certain operations floats having faces of sponge rubber have been used and found very satisfactory. Floats of this type have heretofore involved a board or plate with a sheath of sponge rubber applied thereto by an adhesive, or the like, and in practice this type of construction has not proved altogether satisfactory.

The present invention provides, generally, a plaster working tool characterized by a head, a handle and means coupling the handle to the head, the head being formed of a body of sponge rubber, or the like, having a foraminous metal plate embedded therein. The handle is of simple form involving a grip and standards projecting from the grip to engage the back of the head. The means coupling the head and handle involves posts anchored to the metal plate that is embedded in the head to project from the back of the head and pins are engaged through eyes on the posts and through bores in the handle and have threaded ends that receive retaining nuts.

It is a general object of the present invention to provide a tool of the general character referred to in which the head has a body of sponge rubber, or the like, of suitable size, shape and thickness, while a foraminous plate or sheet of metal is completely embedded in the body of rubber and is substantially coextensive therewith in order to afford effective backing for the working face of the body while at the same time being completely protected or shielded by the body.

A further object of the invention is to provide a simple dependable construction serving to effectively couple a handle to a head of the character referred to. The present invention provides a releasable connection or coupling between the head and handle which in no way interferes with free use of the tool and which connects the handle with the core or metal plate within the body of rubber, providing a rigid dependable structure.

The various objects and features of our invention will be fully understood from the following detailed description of a typical preferred form and application of the invention, throughout

2

which description reference is made to the accompanying drawings, in which:

Fig. 1 is a perspective view of the tool embodying the present invention. Fig. 2 is a detailed sectional view taken substantially as indicated by line 2—2 on Fig. 1. Fig. 3 is a transverse sectional view taken as indicated by line 3—3 on Fig. 2. Fig. 4 is a plan section taken substantially as indicated by line 4—4 on Fig. 2. Fig. 5 is a view similar to Fig. 3, showing the tool after extensive use or following removal of a part of the body to expose the metal core, and Fig. 6 is an end view of the tool showing the head in a deformed condition.

15 The tool provided by the present invention involves, generally, a head or working element A characterized by a body 10 of sponge rubber, or the like, and a foraminous metal core 11 within the body, a handle B characterized by a grip 12 and standards 13, and means C coupling the head A and the handle B, which means is characterized by posts 14 projecting from the head and pins 15 connecting the posts and the handle.

20 The head A of the tool is the work engaging element and in accordance with the present invention it is of simple construction and formation and involves merely the body 10 of sponge rubber or the like and the foraminous plate which is embedded in the body. The body 10 of sponge rubber, or like material, may in practice be of any suitable size or shape, it being preferred ordinarily that it be a rectangular element with a flat bottom or working face 20 and a back face 21 parallel with the working face. The side and end edges 22 may be plain and flat, as shown throughout the drawings. The body 10 may vary considerably in thickness, it being preferred generally that the body be of such thickness as to receive the foraminous plate or core 11, as shown throughout the drawings, and so that there is a working section X of the body below the core or between the core and the working face 20 of such thickness as to give the tool the desired body. It is further desirable that there be a portion Y of the body 10 above the foraminous core or between the core and the back face 21, to provide an effective pad protecting the user's hand or fingers from the foraminous core.

25 The core 11 as provided by the present invention is a plate or sheet of metal completely embedded in the body 10 and in plan configuration it is somewhat smaller than the body 10 so that its several edges 25 are spaced inward somewhat from the edges 22 of the body and are thereby protected by the edge portions of the body.

30 35 40 45 50

Where it is desired to provide a body 10 with a flat working face 20, as shown in Figs. 1 to 3 of the drawings, it is preferred that the core 11 be a flat sheet metal body or plate, in which case the portion X of the body between the core and the working face 20 is of uniform thickness throughout. It is to be understood that, if desired, the body A may be other than flat and by employing a core 11 of sheet metal the body may be given any desired shape within reasonable limits by simply deflecting or deforming the core, as indicated in Fig. 6 of the drawings.

In carrying out the present invention the core 11 is preferably provided with a multiplicity of openings or perforations through it so that it has the general appearance of foraminous sheet metal such as is commonly known as metal lath. It is preferred, however, to employ a core which is somewhat stiffer or heavier than ordinary metal lath, and in the form of the invention illustrated the core is such as to have smooth top and bottom faces 30 and 31, respectively. If foraminous metal plates such as are commonly used as metal lath are employed in carrying out the invention, the faces of the core may be rough or irregular.

The body of sponge rubber, or the like, and the foraminous sheet metal core 11 are permanently combined or joined into a unit by molding, vulcanizing or otherwise handling or treating the material of the body 10 so that the core 11 is embedded or incorporated in the body 10 with portions of the body 10 occupying and continuing through the perforations of the core to thereby integrally bond the portions X and Y of the body. Through thus embedding the core in the body the parts are united so that the body will not separate or peel from the core as is the case where attempts are made to secure facings of rubber or the like to backings or bodies of metal or wood, through the use of adhesives designed for such purpose.

The handle B has a grip 12 that may be shaped and proportioned to be convenient for the hand of a user and the standards 13 of the handle project from the ends of the grip and have enlarged ends or base portions 35 which engage and bear upon the back face 21 of the head A. It is to be understood that in practice the handle B may be varied widely in form and construction and it may be formed either as a unit or as a fabrication employing any suitable material or materials as circumstances require.

The means C provided by the present invention to couple the handle B with the head A involves two pairs of posts 14 extending from the core 11 of the head to project from the back face 21 of the head at points spaced so that the posts receive the standards 13 of the handle. In the preferred form of the invention the posts 14 are permanently or integrally joined with the metal core 11 of head A. In the drawings the posts are shown as integral continuations of bars 40 which are integrally joined to the core 11 by welding material 41.

The posts 14 of each pair are spaced apart to snugly receive a standard 13 of the handle and in the case illustrated an apertured part or eye 43 is provided on the upper end of each post. The standard 13 or handle portion occurring between the posts is provided with a transverse opening or bore 45 and a pin 15 is carried between the eyes of the posts and extends through the bore 45. The pin is provided at one end with a head 46 engaging one eye and is threaded at the other end to carry a retainer 47. The retainer

47 shown in the drawings is in the form of a wing nut threaded on the pin to engage the eye that occurs at the threaded end of the pin. Through the construction just described the handle is effectively connected or coupled to the head A of the tool and the parts may be proportioned so that the portion Y of sponge rubber beneath the base portions 35 of the handle are compressed somewhat when the handle is coupled to the standards, with the result that the structure is tight and is without clearance beneath the standards of the handle where foreign matter might accumulate.

In using the tool provided by the present invention it is gripped by the handle B and it may be manipulated in the manner of an ordinary float to work or handle plaster or other like material. As above pointed out, the head A may be used while flat, as shown in Figs. 1 to 3, or if desired it may be shaped as circumstances require. By employing a sheet metal core 11 of material that can be bent or deformed the tool can be bent into and out of various positions at will. It is to be understood, of course, that if desired the core 11 may be made of a rigid or heavy material so that it remains flat and is not subject to deflection. After extensive use of the tool the portion X of the body 10 may be worn down or away, leaving a part or parts of the core 11 exposed or, if desired, such removal of the body A may be accomplished deliberately in order to expose the core. With the core exposed the tool can be used to advantage as a scratcher or in performing operations quite different from those ordinarily performed by a float.

Having described only a typical preferred form and application of our invention, we do not wish to be limited or restricted to the specific details herein set forth, but wish to reserve to ourselves any variations or modifications that may appear to those skilled in the art, and fall within the scope of the following claims.

Having described our invention, we claim:

1. A tool of the character described including, a head with back and front faces and including, a body of rubber-like material in the form of sponge and a rigid foraminous core in the body and completely covered thereby, and a substantially U-shaped handle having an elongate grip portion and standards at the ends of the grip portion and engaged with the back of the head, the said body having exterior surfaces at the front and back of the head exposed except at the points where the standards of the handle engage the head.

2. A tool of the character described including, a head with back and front faces and including, a body of rubber-like material in the form of sponge and a rigid foraminous sheet metal core in the body and completely covered thereby, and a substantially U-shaped handle having an elongate grip portion and standards at the ends of the grip portion and engaged with the back of the head, the said body having exterior surfaces at the front and back of the head exposed except at the points where the standards of the handle engage the head, the core being the sole reinforcement for the said body.

3. A tool of the character described including, a head with back and front faces and including, a flat body of rubber-like material in the form of sponge and a rigid foraminous core in the body and completely covered thereby, and a substantially U-shaped handle having an elongate grip portion and standards at the ends of the grip

portion and engaged with the back of the head, the said body having exterior surfaces at the front and back of the head exposed except at the points where the standards of the handle engage the head, the core being embedded in the body substantially midway between said exposed exterior surfaces and having edges spaced inward from the edges of the body.

4. A tool of the character described including, a head with back and front faces and including, a body of rubber-like material in the form of sponge and a rigid foraminous core in the body and completely covered thereby, a substantially U-shaped handle having an elongate grip portion and standards at the ends of the grip portion and engaged with the back of the head, the said body having exterior surfaces at the front and back of the head exposed except at the points where the standards of the handle engage the head, and means releasably connecting the handle and head including, posts fixed to the core and projecting from the back of the head and removable fasteners connecting the posts and the standards of the handle.

5. A tool of the character described including, a head with back and front faces and including, a body of rubber-like material in the form of sponge and a rigid foraminous core in the body and completely covered thereby, a substantially U-shaped handle having an elongate grip portion and standards at the ends of the grip portion and engaged with the back of the head, the said body having exterior surfaces at the front and back of the head exposed except at the points where the standards of the handle engage the head, and means releasably connecting the handle and head including, posts fixed to the core and projecting from the back of the head and removable fasteners connecting the posts and the standards of the handle, there being two posts at each standard adjacent opposite sides of said standard.

site sides thereof, and each fastener being engaged through a standard and with the posts at opposite sides of the standard.

6. A tool of the character described including, a head with back and front faces and including, a body of rubber-like material in the form of sponge and a rigid foraminous core in the body and completely covered thereby, a substantially U-shaped handle having an elongate grip portion and standards at the ends of the grip portion and engaged with the back of the head, the said body having exterior surfaces at the front and back of the head exposed except at the points where the standards of the handle engage the head, and means releasably connecting the handle and head including, posts fixed to the core and projecting from the back of the head and fasteners connecting the posts and the standards of the handle, there being two posts at each standard adjacent opposite sides thereof, the posts having openings through them at parts opposite the standards and each fastener being a screw fastener with a pin portion slidably engaged through a standard and through the openings of the posts adjacent said standard, a head on one end of the pin portion engaging the post at one side of the said standard, and a nut threaded on the pin portion and engaging the post at the opposite side of said standard.
